FOLDAWAY SEATING PLATFORM
Louis A. Antonioli, 2504 Autumnwood Drive,
Glenshaw, Pa. 15116
Filed Sept. 30, 1966, Ser. No. 583,375
19 Claims. (Cl. 297—232)

ABSTRACT OF THE DISCLOSURE

There is disclosed a foldaway seating arrangement for use in co-operation with an auditorium railing and the like, said arrangement comprising a platform having foldable legs, said legs being extendable to position said platform adjacent a lower run of said railing in the operative position of said platform, seating means mountable on said platform, and rail engaging means secured to said platform for engaging an upper run of said railing to at least aid in suspending said platform from said upper railing run in a foldaway stored position of said platform and said seating means.

My present invention relates to foldaway seating platforms for use in auditoria, arenas and other places of large seated congregations, and more particularly to platform arrangements of the character described for use in cooperation with the steel or other type of railing conventionally provided in such auditoria and the like to define the aisles and seating sections thereof.

Conventionally it has been the practice in the operation of auditoria and the like, when unusually large crowds are anticipated, to provide large numbers of folding chairs to accommodate the overflow crowd. The folding chairs usually are placed in the aisles of the auditorium immediately behind the railing usually provided to delineate such aisles, particularly at the edges of balconies or other elevated seating section. Because the aisles usually are recessed considerably below the adjacent rows of permanent seats, temporary platforms are placed thereon, at convenient positions adjacent the railing so that the spectators in the temporary seating arrangements are seated at the proper elevation for viewing the stage or the like over the heads of the audience in front of them and over the railing itself.

The installation and subsequent removal of these temporary platforms with the required folding chairs thereon involves considerable time, labor and expense, in addition to the fact that the temporary platforms frequently become displaced from the railings by the press of the crowds passing through the aisles so as to distort the temporary seating arrangement and to block the remainder of the aisles. Moreover, the storing of the temporary platforms, which are relatively large and bulky, together with the folding chairs used therewith requires considerable space and involves considerable expense not only in the provision of the storage facilities but also in the time and labor involved in transporting the platforms and folding chairs to and from the place of storage.

I have solved these problems by providing novel forms of foldaway seating arrangements. In one form, the elevated platform for the folding chairs is provided with novel means both for temporary or permanently securing the platform as desired to the aforementioned railing during operation thereof to prevent displacement of the platform from the railing. When not in use my novel platform is provided with additional cooperating means for securing or suspending the unused platform against the railing for storage purposes in a position such that no appreciable obstruction is offered to the aisle adjacent the railing. In another arrangement of my invention the platform is provided with additional novel means for supporting the

2

chairs when folded in the stored position of the platform, such that both the chairs and the platforms can be mounted in stored positions on those railing sections at which the platforms are periodically used. The last-described arrangement of my invention wherein both the platform and the chairs are stored in situ likewise offers no appreciable obstruction to the adjacent aisles.

In still another arrangement of my invention foldable seat means are foldably or hingedly secured to each of the seating platforms, and the latter are pivotally or otherwise secured to the auditorium railing in such manner that both the platform and the folding seat means foldably secured thereto can be moved between their stored and operative positions with a minimum number of manipulations thereof, with the result that the time for setting-up and storing the last-mentioned foldaway seating arrangement is further reduced. The foldable seat means is provided either in the form of discrete folding chairs or of a continuous folding bench extending along the length of a given platform, with either the folding chair arrangement or the folding bench being hingedly or otherwise foldably secured to the platform. When not in use the platform with its folded seat means can be pivoted or otherwise moved to a suspended, storing position on that section of auditorium railing at which the seating platform is used for temporary seating purposes.

In my first mentioned foldaway seating arrangement the necessary separate storage space is considerably reduced inasmuch as the bulkiest part of the seating arrangement, viz. the platforms, is stored at the location of their occasional use. In this case it is only necessary to convey the folding chairs to and from the storage facilities therefor. In the remaining arrangements of my novel seating platform both the platform and the chairs or bench used thereon are stored at the location of their use so that the aforementioned storage facilities are eliminated altogether and likewise the necessity of conveying folding chairs or the like to and from the locations of their use. In very large arenas or auditoria, such as are in use at the present time, the savings resulting from decreased labor and the elimination of costly storage facilities for conventional temporary seating arrangements are very considerable.

During the foregoing discussion, various objects, features and advantages of the invention have been alluded to. These and other objects, features, and advantages of the invention, together with construction details thereof, will become apparent as the following description of certain presently preferred embodiments of the invention and certain presently preferred methods of practicing the same proceeds.

In the accompanying drawings I have shown certain presently preferred embodiments of the invention and have illustrated certain presently preferred methods of practicing the same in which:

FIGURE 1 is a partial isometric view of one form of a temporary seating arrangement including a temporary seating platform provided for folding chairs or the like and arranged in accordance with my invention;

FIGURE 2 is an end elevational view of the seating arrangement shown in FIGURE 1;

FIGURE 3 is an end elevational view of the seating arrangement shown in FIGURES 1 and 2 but illustrated here in the foldaway or stored position of the platform;

FIGURE 4 is a partial isometric view of another form of foldaway seating arrangement in accordance with my invention and illustrating means for storing both the platform and the folding chairs used thereon at the location of their use;

FIGURE 5 is an end elevational view of the seating arrangement shown in FIGURE 4;

FIGURE 6 is a partial isometric view of still another form of my foldaway seating arrangement showing inter-

connected foldaway platform and seating means in their operative position;

FIGURE 7 is an end elevational view of the seating arrangement of FIGURE 6;

FIGURE 8 is a partial isometric view showing the seating arrangement of FIGURES 6 and 7 in its fold-away position; and,

FIGURE 9 is an end elevational view of the seating arrangement as shown in FIGURE 8.

Referring now more particularly to FIGURES 1 to 3 of the drawings, the exemplary form of novel, foldaway seating arrangement 10 shown therein is arranged for use in cooperation with railing 12 usually provided in arenas, auditoria and the like as mentioned previously. The railing 12, therefore, usually includes a number of standards or supports 14 and horizontal runs 16. Usually the standards and runs 14, 16 are fabricated from steel pipe and suitable fittings (not shown) provided for example to connect sections of the pipe. However, railings of other construction are obviously contemplated.

The seating arrangement 10 proper includes a platform or table 18 having foldable legs 20 and 22 adjacent the front and rear edges thereof respectively. The legs, 20, 22 in this example are provided with conventional hardware indicated generally by reference character 24 of a collapsible nature. In this arrangement it is contemplated that a number of the tables 18 be provided and distributed along the length or lengths of the railing 12 as required for the anticipated excess crowds. For convenience in handling, each of the tables 18 is provided in such length to accommodate in the order of about six folding chairs 26. It is to be understood, however, that the number of chairs 26 supported on a given table 18 can be varied as desired, along with the length of the table. Desirably the chairs 26 are positioned along the length of the table or platform 18 and prevented from displacement across the top surface 28 thereof by means of an apertured strip 30 secured to the top 28 of the table and extending in this example along the rear lateral edge portion of the table 18. The strip 30 is provided with a number of apertures 32 which are spaced to receive in this example the lower end portions 34 of the rear chair legs 36. Desirably the apertures 32 extend entirely through the safety strip 30 so as not to cause the chair 36 to be tilted forward.

Railing engaging means including a number of 2-positioned brackets 38 are secured at spaced intervals along the front edge portion of the table 18 as better shown in FIGURE 1. In this example, three such brackets are so utilized, although the number obviously can be varied, depending on the application of the invention. Each of the brackets 38 includes an angular or bracket section 40, whereby the brackets 38 are secured to the table 18, and a first arcuate section 42 for complementary engagement over the adjacent top surface of the lower run 16A of the railing 12. It is contemplated of course that a shape other than that shown can be imparted to the brackets section 42 depending upon the given cross sectional configuration of the railing run 16A. The brackets 38 as thus far described thus prevent the table 18 from being displaced rearwardly of the railing 12 and from consequently blocking the remainder of aisle 44. It is also contemplated that sufficient structural strength can be imparted to the brackets 38 or that additional numbers thereof can be provided as desired to support entirely the front portion of the table 18, in which case the front legs 20 thereof can be eliminated, where permitted by applicable codes.

As better shown in FIGURE 3 of the drawings the 2-positioned bracket 38 has an additional function. When the sitting arrangement 10 is not in use, the table 18 is stored at the location of its use by securing the table 18 to the railing 12. In the latter arrangement of the invention the bracket 38 is provided with an additional arcuate section 46 adjacent the outer end portion thereof so that the table 18 with its legs 20, 22 now in their folded positions,

can be suspended from the uppermost run 16B of the railing 12. It will be seen in the arrangement shown that the table 18 can be thus stored on the railing 12 on either the front or rear side thereof. In any event the table 18 when in its stored position as shown in FIGURE 3 offers little or no obstruction to the adjacent aisle 44. With this arrangement only the folding chairs 26 have to be conveyed from and to additional storage facilities therefor. The bulkier platforms such as the platform 18, however, can be secured along the length of the railings such as the railing 12 at the respective locations of their subsequent use.

To prevent inadvertent removal of one or more of the tables 18 additional, cooperating railing engaging means including brackets 48 can be secured along the rear edge portion of the table 18 in accordance with another feature of the invention. The brackets 48 are of single position construction and include base section 50 for securage desirably to the underside of the table 18 and an arcuate section 52 adjacent the outer or free end of the brackets 48. The brackets 38 and 48 desirably are fabricated from a resilient structural material such as hot rolled steel so that, when the brackets 38 are initially engaged over the top run 16B of the railing 12, the co-operating brackets 48 can be snapped under the adjacent surfaces of the lowermost run 16A. This produces a snapped-in clamping action to secure or suspend the table 18 in its stored position against the railing 12. The arcuate sections 46 and 52 of the brackets 38 and 48 respectively can be varied to suit the configurations of railing runs 16A, 16B as described previously in connection with arcuate sections 46 of the brackets 38.

In the event that the brackets 38, 48 are not sufficiently resilient or that the cross sectional configuration of railing runs 16A, 16B do not lend themselves to the aforescribed, co-operative snap action of the brackets, at least the lower brackets (as viewed in FIGURE 3) are secured to the table 18 with wing nuts or thumb screws 54 to permit loosening of the brackets 48 and fitting 40 around the railing runs, such as runs 16A, 16B followed by tightening the thumb screws 54 to clamp the table against the adjacent portion of the railing 12.

With reference now to FIGURES 4 and 5 of the drawings a modified form 10' of my seating arrangement is illustrated wherein similar reference characters with primed accents refer to similar components of FIGURES 1 to 3. In the open or operative position (not shown) of the seating arrangement 10' the disposition of the various components is substantially as shown in FIGURES 1 and 2 of the drawings. Thus, the table 18' in its unfolded or operative position is stabilized or supported as desired at the lowermost railing run 16'A by railing engaging means including arcuate section 42' of each 2-position bracket 56. In the stored position of the table 18' the brackets 56 cooperate with additional railing engaging means including brackets 58 to spacedly secure the table 18' to railing runs 16'A and 16'B. In furtherance of this purpose the brackets 56, 58 are provided with intermediate elongated sections 60 and 62 respectively to space their 60 rail engaging sections 46' and 52' farther outwardly from the table 18' in comparison with the brackets 38, 48 of the table 18 in FIGURES 1 to 3. The brackets 56, 58 otherwise function in much the same manner as the brackets 38, 48 described above with reference to FIGURES 1 to 3.

This outward spacing of the table 18' from the railing 12' affords a storage space 64 into which those chairs 26' which are utilized with a given one of the tables 18' are inserted in their folded positions as illustrated. 70 The chairs 26' when thus stored are supported and thus prevented from sliding downwardly from between the railing 12' and the juxtaposed table 18' by means of an elongated supporting strip 66 secured by suitable means along the lower lateral edge 68 of the table 18', as viewed in FIGURES 4 and 5.

The form of my seating arrangement of FIGURES 4 and 5 presents the added advantage of providing storage for both the platforms 18' and the folding chairs 26' used thereon at each location of their use. In the foldaway position of the platform 18' and chairs 26' a very compact arrangement is obtained which does not introduce any substantial obstruction into the adjacent aisle.

supporting said platform adjacent a run of said railing, railing engaging means adjacent the forward edge of said platform for engaging said railing run to position said platform adjacent said railing in the operative position thereof, and additional railing engaging means adjacent the rear edge of said platform for engaging a run of said railing to at least aid in suspending said platform from said railing run in the foldaway stored position thereof.

2. A foldaway seating arrangement for use in cooperation with an auditorium railing and the like, said arrangement comprising a platform having foldable legs, railing engaging means adjacent the forward edge of said platform, said railing engaging means having a first run-engaging portion shaped to engage a first run of said railing to prevent displacement of said platform therefrom in its operative position and having a second run-engaging portion shaped to engage a second run of said railing to suspend said platform in a foldaway stored position thereof.

3. The combination according to claim 1 wherein an apertured chair positioning strip is secured to the supporting surface of said platform and extends generally parallel to said railing along the length of said platform.

4. The combination according to claim 2 wherein additional railing engaging means are positioned adjacent the rear edge of said platform for engaging a railing run to clamp said platform in the foldaway position thereof in cooperation with the second portion of said first-mentioned railing engaging means.

5. The combination according to claim 4 wherein said additional railing engaging means each have a run-engaging portion disposed generally in opposition to the juxtaposed second run-engaging portion of said first-mentioned rail engaging means, and said first and said second rail engaging means are resilient so that said last-mentioned run-engaging portions can be snapped over and under adjacent portions respectively of said first and said second railing runs.

6. The combination according to claim 1 wherein at least said additional railing engaging means are elongated to space said platform from said railing in the foldaway position thereof, said platform and said railing defining a space therebetween for storing folding chairs utilized with said platform, and chair supporting means are secured to said platform for retaining said chairs within said space.

7. The combination according to claim 1 wherein said first-mentioned railing engaging means are pivotally secured to a first railing run, foldable seating means are hingedly joined to said platform, means are provided for securing said foldable seating means in an upright position thereof when said platform is pivoted to its operative horizontal position about said first railing run, and said additional railing engaging means are disposed to engage a second railing run for securing said platform to said second railing run in upright foldaway positions of said platform and of said seating means.

8. The combination according to claim 7 wherein said foldable seating means are hingedly joined to a supporting strip extending along the length of said platform said strip having a height relative to the surface of said platform to permit folding back and seat and leg sections of said seating means in a generally parallel array thereof against said platform in the inoperative position thereof.

9. The combination according to claim 8 wherein said seating means include hingedly joined back and seat and leg panels each extending substantially along the entire length of said platform.

10. The combination according to claim 8 wherein said seating means include a plurality of individual foldable chairs, each of said chairs including a back panel hingedly joined to said supporting strip and a hinged seat and leg panel arrangement hingedly joined to said back panel.

11. The combination according to claim 8 wherein the lower edge section of said leg portion is insertable in the operative position thereof into a grooved stabilizing strip secured to said platform and extending substantially along the entire length of the supporting surface thereof, said leg section being retractable therefrom to permit folding of said seating means.

12. The combination according to claim 9 wherein said platform extends laterally outwardly of said supporting strip, and said additional railing engaging means are secured to the lateral extension of said platform and are thereby positioned outwardly of said supporting strip.

13. The combination according to claim 1 wherein said first-mentioned railing engaging means are pivotally engageable with a first railing run about which said platform is pivotable between its operative position and its foldaway stored position, and said additional rail engaging means are securable to a second railing run to secure said platform in its last-mentioned position.

14. The combination according to claim 1 wherein foldable seating means are foldably secured to said platform.

15. The combination according to claim 14 wherein means are provided for securing said foldable seating means in an upright position thereof when said first-mentioned railing engaging means are engaged with the first-mentioned railing run and said platform is positioned in its operative position.

16. The combination according to claim 14 wherein said seating means include a plurality of individual foldable chairs, each of said chairs being foldably joined to said platform.

17. The combination according to claim 14 wherein at least said additional railing engaging means are elongated in the projecting direction thereof relative to said platform to permit storing of said seating means between said platform and said railing in the inoperative suspended position of said platform.

18. A foldaway seating arrangement for use in cooperation with an auditorium railing and the like, said arrangement comprising a platform having foldable legs, said legs being positionable to support said platform adjacent a lower run of said railing in the operative position of said platform, foldable seating means foldably secured to said platform, and railing engaging means secured to said platform for engaging an upper run of said railing to suspend said platform from said upper railing run in the foldaway stored position of said platform and of said seating means.

19. A foldaway seating arrangement in combination with an auditorium railing, said arrangement comprising a platform, means secured to said platform for positioning said platform relative to a lower run of said railing in the operative position of said platform, means for securing foldable seating means to said platform, and railing engaging means secured to said platform for suspending said platform from an upper railing run with said seating means disposed between said platform and said railing in a foldaway stored position of said platform and of said seating means.

UNITED STATES PATENT OFFICE
CERTIFICATE OF CORRECTION

Patent No. 3,394,963

July 30, 1968

Louis A. Antonioli

It is certified that error appears in the above identified patent and that said Letters Patent are hereby corrected as shown below:

Column 1, line 58, "or" should read -- of --; line 62, "temporary" should read -- temporarily --. Column 3, line 52, "includes" should read -- include --. Column 4, line 15, "is" should read -- in --; line 21, "brackets", first occurrence, should read -- bracket --. Column 5, line 44, "jointed" should read -- joined --. Column 8, line 2, "section" should read -- portions --; same line 2, "portion" should read -- section --; same line 2, "is" should read -- are --.

Signed and sealed this 3rd day of February 1970.
